Re. 15,809

UNITED STATES PATENT OFFICE.

JOSEPH F. BARTINI, OF ALEXANDRIA, VIRGINIA, ASSIGNOR OF ONE-HALF TO HOWARD
B. ECCLESTON, OF WASHINGTON, DISTRICT OF COLUMBIA.

BREAD CUTTER AND CARRIER.

Original No. 1,345,118, dated June 29, 1920, Serial No. 321,564, filed September 4, 1919. Application for
reissue filed June 21, 1921. Serial No. 479,383.*To all whom it may concern:*

Be it known that I, JOSEPH F. BARTINI, a citizen of the United States, residing at Alexandria, in the county of Alexandria and 5 State of Virginia, have invented certain new and useful Improvements in Bread Cutters and Carriers; and I do hereby declare the following to be a full, clear, and exact description of the invention, such as will enable others skilled in the art to which it 10 appertains to make and use the same.

This invention relates to a bread cutter and carrier which is adapted for use in various types of institutions, such as homes for 15 soldiers, aged people or the like, and the primary object of the invention is to provide a device which will materially facilitate the cutting and passing of bread to the persons seated at a table.

Another object of this invention is to provide an endless conveyer which is mounted upon the table intermediate the edges of the same and for travel longitudinally over the top of the table for carrying slices of bread 25 thereover so that the persons seated at the table may readily reach the bread and remove it from the conveyer when desired, and further to provide a pan or box for receiving any slices of bread which might have 30 passed the entire length of the table without being removed from the conveyer.

A further object of this invention is to provide a rotary knife and a bread retaining cylinder, through which the bread is fed by 35 gravity so that it will be sliced by the knife.

Another object of the invention is to provide a cutting or slicing device in which the bread or other material to be sliced is fed by gravity, combined with a relatively 40 stationary cutting edge, the edge in the embodiment shown being a rotary knife, the article to be sliced being movable toward and away from the cutting edge.

With the foregoing and other objects in 45 view, this invention consists in such novel features of construction, combination and arrangement of parts as will be hereinafter more fully described, illustrated in the accompanying drawings and claimed.

In describing the invention in detail, reference will be had to the accompanying drawings, wherein like characters designate

like and corresponding parts throughout the several views, and in which:

Figure 1 is a top plan view of the invention, showing it applied to a table. 55

Figure 2 is a side elevation of the table, showing the application of the improved bread cutter and carrier.

Figure 3 is an enlarged view, showing 60 the bread cutting structure and a portion of one end of the conveyer.

Figure 4 is an end view of the invention.

Figure 5 is a perspective view of one of 65 the bread carrying plates of the conveyer structure.

Figure 6 is a side elevation of a modified form of the bread retaining cylinder, and

Figure 7 is an edge view of the structure 70 illustrated in Figure 6.

Referring more particularly to the drawing, 1 designates an ordinary table which is supported by the usual type of supporting legs 2. The table top 3 has a conveyer structure generically indicated by the numeral 4 placed thereon and extending longitudinally of the table in the center of the top, as clearly shown in Figure 1 of the drawings. The conveyer structure 4 includes supporting side rails 5 which are supported above the table by suitable supporting legs 5'. The conveyer proper, which is composed of a plurality of bread carrying plates 6 and links 7, travels over rollers 8 and 9, which are carried by the side rails 85 5. The bread carrying plates 6 have their ends rolled, as shown at 10, to provide an upstanding portion for engaging one edge of a slice of bread so that the bread will be carried along with the movement of the 90 plates and prevented from slipping or accidentally passing off the plate. The links 7 are composed of hingedly connected sections 11 and 12 which are hinged together as shown at 13 so as to permit the conveyer 95 to pass over the rollers 8 and 9, as clearly shown in the drawings.

The propelling roller 9 is mounted upon a shaft 14, which shaft extends beyond the edge of the table top 3 and has a pulley 15 100 mounted thereon about which a belt 16 passes. The belt 16 may be connected to any suitable type of prime mover or propelling means for rotating the shaft, and

consequently rotating the roller and for operating the conveyer 6.

The side rails 5 have their ends positioned at the delivery end of the conveyer structure turned downwardly, as shown at 17, for guiding slices of bread into a receiving box 18 which is supported by suitable brackets 19. The brackets 19 are attached to the table 1 in any suitable manner.

- 10 The shaft 14 has a beveled gear 20 mounted thereon which meshes with a second beveled gear 21 carried by a vertical shaft 22. The vertical shaft 22 extends through the table top 3 and has a pulley 23 mounted upon its lower end, about which a belt 24 travels. The belt 24 also travels about a pulley 25 mounted upon a vertical shaft 26. The shaft 26 is mounted in a sleeve 34 carried by the bracket 27, which is secured to 20 the table top 3. The upper ends of sleeve 34 and shaft 26 are formed with annular bearing portions 35 and 36, respectively, which may form races for ball or roller bearings, if desired.
- 25 The shaft 26 has a circle knife 28 carried by its upper end, which knife is provided with peripheral teeth 29 which slice the bread.

The bread is retained and fed to the knife 28 by a cylinder or gravity-feed holder 30, which cylinder or holder is supported by an arm 31. The arm 31 is pivotally connected, as shown at 32, to one of the side rails 5 of the conveyer structure. The cylinder 30 may be shaped to fit a loaf of bread. An arm 33 is supported on the sleeve 34, and it may be adjustably mounted thereon. The edge of the bread beneath the lower open end of the cylinder rests upon the arm 33, and hence the adjustment of the arm regulates the thickness of the bread. The arm extends outwardly beneath the different positions of the cylinder 30 and prevents the bread from falling out of the cylinder upon the table.

In the operation of the improved bread cutter and conveyer the lower end of the loaf of bread will extend out of the cylinder 30 and rest upon the arm 33, after which 50 the cylinder is swung upon its pivot 32 so that the knife 28 during its rotation will engage and pass through the loaf of bread, slicing a slice off the same, which slice of bread falls upon one of the plates 6 and is carried along over the table top 3 until it is taken from the conveyer by a person seated at the table. In case the bread is not taken from the conveyer, it will be deposited in the box 18, from whence it may be taken and used for any purpose, or replaced upon the receiving end of the conveyer.

In Figures 6 and 7 of the drawings a modified form of the bread holder is illustrated. The modified form comprises a pair

of arcuated plates 40 and 41 which engage a loaf of bread on opposite sides of the same and hold it in proper position for feeding to the knife 28. The plates 40 and 41 have brackets 42 attached thereto to 70 which the supporting arms 43 of the members are rotatably attached.

From the foregoing description taken in connection with the accompanying drawings the advantages of construction and of method of operation of the improved bread cutter and carrier will be readily apparent to those skilled in the art to which the invention appertains, and, while in the foregoing description the principle of the operation of this invention has been described, together with various features of construction, it is to be understood that certain minor features of construction, combination and arrangement of parts may be altered 80 to suit practical conditions, provided such alterations are comprehended within the scope of what is claimed.

What is claimed is:

1. In a slicing machine, a rotary knife, 90 a holder for the material to be sliced, said holder so constructed that the material will pass downwardly therethrough by gravity, said holder mounted to oscillate toward and from the rotary knife.

2. In a slicing machine, a rotary knife, a holder for the material to be sliced, said holder so constructed that the material will pass downwardly therethrough by gravity, said holder mounted to oscillate toward and 100 from the rotary knife, a gauge plate on which the material rests while being sliced, said gauge plate being so constructed that the material will fall therefrom as it is sliced.

3. In a slicing machine, a rotary knife, a holder for the material to be sliced, said holder so constructed that the material will pass downwardly therethrough by gravity, said holder mounted to be moved toward 110 and from the rotary knife, a gauge plate on which the material rests while being sliced, said gauge plate being so constructed that the material will fall therefrom as it is sliced.

4. In a slicing machine, a rotary knife, a holder for the material to be sliced, said holder so constructed that the material will pass downwardly therethrough by gravity, said holder mounted to be moved toward 120 and from the rotary knife, a gauge plate on which the material rests while being sliced, said gauge plate being relatively narrow as compared to the width of the material to be sliced, whereby the material will fall from 125 the plate as it is sliced.

5. In a slicing machine, a rotary knife, a holder for the material to be sliced, said holder so constructed that the material will pass downwardly therethrough by gravity, 130

105

15,809

3

- said holder mounted to be moved toward and from the knife, an adjustable gauge plate on which the material rests, said gauge plate being positioned below the knife and 5 extending beyond the periphery thereof.
6. In a slicing machine, a table, a knife rotatably mounted thereon, an oscillatable gravity-feed holder connected to said table, and an endless conveyer for removing the 10 material sliced.
7. In a slicing machine, a table, a sleeve secured to said table, a shaft rotatably mounted in said sleeve, a knife on said shaft, and an oscillatable gravity-feed holder on 15 said table.
8. A slicing machine, including a table, a sleeve secured to said table, a shaft in said sleeve, a knife on said shaft, an oscillatable gravity-feed holder on said table, and means 20 on said sleeve for regulating the thickness of the slices.
9. In a slicing machine, a support, a shaft journaled on the support, shaft rotating means, a knife fixed to the shaft for rotation therewith, an arm pivoted to the support, a receptacle fixed to the arm and adapted to retain the article to be sliced, said arm and receptacle adapted to be swung toward and 25 from the knife.
10. In a slicing machine, a support, a shaft journaled on the support, shaft rotating means, a knife fixed to the shaft for rotation therewith, a holder pivotally mounted on the support and adapted to retain the article to be sliced, and an out- 30
- standing arm disposed below the knife to engage the end of the object to support the same in position to be engaged by the knife. 40
11. In a slicing machine, a support, a vertically disposed shaft journaled on the support, shaft rotating means, a circular knife 45 fixed to the shaft for rotation therewith, an upstanding arm pivoted to the support, a tubular member fixed to the upper end of the supporting arm and adapted to retain the object to be sliced, the arm being adapted to be swung to a position where the tubular member will be disposed above the circular knife at one edge thereof, and an outstanding arm carried by the shaft and disposed below the knife to engage the end 50 of the object to support the same in position to be engaged by the knife. 55
12. In a slicing machine, a support, a vertically disposed shaft journaled on the support, shaft rotating means, a circular knife 60 fixed to the shaft for rotation therewith, an upstanding arm pivoted to the support, a tubular member fixed to the upper end of the arm and adapted to retain the object to be sliced, the arm being adapted to be swung 65 to a position where the tubular member will be disposed above the knife at one edge thereof, an outstanding arm carried by the shaft and disposed below the knife to engage the end of the object to support the same in position to be engaged by the knife, and a carrier adapted to convey the slices away from the knife. 70

JOSEPH F. BARTINI.
